UNITED STATES PATENT OFFICE.

ALBERT I. GALLAWAY, OF ST. LOUIS, MISSOURI.

PHONOGRAPH-RECORD HOLDER.

1,407,938.

Specification of Letters Patent. Patented Feb. 28, 1922.

Application filed August 7, 1919. Serial No. 315,928.

To all whom it may concern:

Be it known that I, ALBERT I. GALLAWAY, a citizen of the United States of America, and a resident of the city of St. Louis and State of Missouri, have invented certain new and useful Improvements in a Phonograph Record Holder, of which the following is a specification.

The primary object of this invention is to provide an improved holder for phonograph records whereby the records will be held in approximately vertical positions against one another, thereby reinforcing each other against warping.

Another object is to provide an improved phonograph record holder which can be used as a carrier for the records.

Other and further objects will appear in the specification and be specifically pointed out in the appended claims, reference being had to the accompanying drawings exemplifying the invention, and in which,

Figure 1 is a plan view of this improved record holder in which is contained a plurality of phonograph records.

Figure 2 is an end elevation of Fig. 1.

Figure 3 is a side elevation of Fig. 1.

Figure 4 is a side elevation of the holder showing the records removed.

Referring to the drawings this improved record holder is constructed of relatively stiff wire and bent so as to form a pair of compartments 1 which are adapted to contain a plurality of suspended and approximately vertically held phonograph records.

Each compartment is further comprised of a pair of end members 2, each having a pair of converging side members 3 and a bottom member 4; each bottom member having a side member 5 and a pair of transversely extending portions 6.

Each compartment 1, which is comprised of the parts just described, is constructed of a single piece of wire, and in the manufacture of this improved holder, the pair of pieces of wire from which this improved holder is made, are twisted or twined together, as designated at 7, the twisting operation being carried on after the legs 8 which extend upwardly from the transverse portion 6 have been formed, said twisting 7 of the pairs of wires while serving to hold the compartments 1 in their adjacent positions, also serving as a reinforcement to the

compartments when the compartments are 55 filled with records.

As shown more clearly in Fig. 2, the upwardly extending legs 8 incline towards each other relative to being engaged and forming the twisted portions, thereby forming 60 triangular spaces or recesses 9 between each pair of legs 8 and below the twisted portions 7, and where the portions 10 of the pairs of wires diverge after the twisted portions have been made, recesses 11 are formed. 65

Looping through each opposing pair of recesses 9 and 11, as shown more clearly in Figs. 2 and 4, is a looped end 12 of a lifting handle 13, and since both of the compartments 1 are tied together by the twistings 7 of the wires, said handle serves as a lifting element to both of the compartments. 70

As already related in one of the objects of this invention, the prime idea is to mount and hold a plurality of phonograph records 75 in approximately vertical positions and in abutting position relative to one another, so that each and every one of the records will tend to form a compact body, so that no sagging or warping will be effected in a single 80 record, as it is well known that when phonograph records are left in leaning positions in separate compartments in warm and damp places, softening of the material of which the record is made will take place, thereby 85 allowing the records to become bent or warped.

This improved form of record holder can be made in different sizes relative to the different standards of records, and in the ordinary manipulation thereof, a plurality of records is generally contained in each compartment so that when in the playing of the records on the phonograph, the records of one compartment can be first taken up in 95 order from the side designated as A and after a record has been played, upon replacing the record in this compartment, the B side of the compartment is engaged and the record placed down therein, and on account of the inclination of the side members 3 as relating to each end member 2 of a compartment, the record being deposited will be forced against an adjacent record so that it will seat fully against said 100 adjacent record. The next record to be played on the phonograph is taken from the A side as already related relative to the first 105

record played or removed, in which no misplacing of records will occur.

This improved holder containing a plurality of records when not in use can readily be placed away in a cabinet or the like.

Another advantage of this improved holder is in the provision of the adequate means provided for transporting a plurality of records from place to place, as it is quite common at the present time for a small phonograph to be taken to picnics or boating outings or the like. So that the records will not fall from the holder during transports, means are provided by the end members 2 for preventing accidental removal. In this connection, attention is called to Fig. 3, which discloses that each pair of end members 2 of each compartment are held apart a distance lesser than the diameter of the records, as shown by the dotted lines C, said end members 2 being held a distance above the center D of the records when the records are in the holder, said members 2 being engaged by the opposing portions of the periphery of the record, and forced outwardly by the record as they are withdrawn or replaced in the respective compartments, such provision of the forcing apart of the end members 2 during the withdrawal of any record preventing any record from being accidentally removed in carrying.

What I claim is:

1. A phonograph record holder comprising end members and side members for holding the records in approximately vertical positions, one of said side members being shaped so as to form a guiding member, in which the guiding member will tend to force each record being inserted in the holder towards the records contained in the holder and a bottom member serving as a support to said end and side members.

2. A phonograph record holder comprising end members and side members, said side members at their point of intersection with their respective end members being angularly inclined, and a bottom member related to said end and side members said end members being arranged on a plane

above the horizontal center of the records when records are placed edgewise there between.

3. A phonograph record holder comprising end members and side members, the side members of one side being disconnected thereby providing means for allowing the end members to be resiliently sprung apart, and a bottom member serving as a support to said end and side members and to upended phonograph records, said end members being arranged at a height above said bottom member, wherein they will engage the records on a plane above their horizontal center.

4. A holder for upended phonograph records comprising a pair of straightly formed, resiliently held, oppositely disposed parallel members, a bottom member arranged beneath said other members and providing a support thereto, said pair of opposing members adapted to engage the records on a plane above their horizontal centers.

5. A holder for upended phonograph records comprising a pair of straightly formed, resiliently held, oppositely disposed parallel members, a bottom member arranged beneath said other members and providing a support thereto, said pair of opposing members adapted to engage the records on a plane above their horizontal centers, each of said end members having an inclining portion extending from each end thereof.

6. A phonograph record holder having a pair of compartments, each being comprised of end members and side members, the side members on one side of each compartment being disconnected, thereby providing means for allowing the end members to be resiliently sprung apart, a bottom member for each of said compartments, each pair of end members of each compartment being arranged on a plane above the horizontal center of the records when the records are mounted on edge in a respective compartment, said side members at their point of intersection with their respective end members being angularly inclined.

ALBERT I. GALLAWAY.
